UNITED STATES PATENT OFFICE

148,516

DESIGN FOR AN AUTOMOBILE

Frank Brogan, Cincinnati, Ohio

Application April 3, 1946, Serial No. 128,208

Term of patent 14 years

(Cl. D14—3)

To all whom it may concern:

Be it known that I, Frank Brogan, a citizen of the United States of America, residing at Cincinnati, in the county of Hamilton, State of Ohio, have invented a new, original, and ornamental Design for an Automobile, of which the following is a specification, reference being had to the accompanying drawing, forming part thereof.

Fig. 2 is a front elevational view of the same.

Fig. 3 is a top plan view of the same.

The side of the automobile opposite to that illustrated upon Fig. 1, is substantially the same as the side shown.

I claim:

The ornamental design for an automobile, as shown and described.

FRANK BROGAN.
